UNITED STATES PATENT OFFICE.

AUGUST S. ROTHSCHILD, OF BUFFALO, NEW YORK, ASSIGNOR OF ONE-HALF TO DAVID B. LEVI, SIEGFRIED LEVI, AND ERNST LEVI, ALL OF BUFFALO, NEW YORK.

HOOKLESS FASTENER.

Application filed February 24, 1927. Serial No. 170,621.

This invention relates to a hookless fastener of the type in which two longitudinal rows of coupling members are moved into and out of engagement with each other by a slide for the purpose of closing the opening between the parts on which the rows of coupling members are mounted, or opening the same, such fasteners being now commonly employed on purses, bags, tobacco pouches, garments, shoes and elsewhere.

As heretofore constructed such hookless fasteners have been unsatisfactory for use on the front edges of sweaters and similar garments and similar cases where it is desirable to completely disconnect the parts on which the coupling members are mounted because a sweater equipped with such fastener must be drawn over the head when putting on and taking it off the body instead of permitting the same to be used like an ordinary open front coat or jacket.

It is the object of this invention to provide a slide hookless fastener of this character which is divided into sections capable of being connected and disconnected so that the slide will operate as a unit when its sections are united and permit of connecting and disconnecting the two rows of coupling members for closing and opening the garment more or less and also permitting of completely disconnecting the parts of the joint between the parts thereof.

In the accompanying drawings:

Figure 1 is a plan view of a hookless fastener embodying my invention.

Figure 2 is a fragmentary longitudinal section, on an enlarged scale, taken on line 2-2 Fig. 3.

Figure 3 is a transverse section taken on line 3-3 Fig. 2.

Figure 4 is a longitudinal section taken on line 4-4 Fig. 3.

Figures 5 and 6 are perspective views of the two sections of the slide which embodies my improvements.

Figure 7 is a similar view of the lock for connecting and disconnecting the sections of the slide.

Figure 8 is a similar view of the catch and associated parts for holding the lock in its operative position and manipulating the same.

In the following description similar reference characters indicate like parts in the several figures of the drawings:

The numerals 10, 11 represent two strips of webbing or other woven or flexible material which are secured to the opposing edges of the parts which are to be connected, such as for example as the opposing edges of the front parts of a garment which is adapted to be completely separated for opening the garment and to be connected for closing the joint between these parts when the garment is worn. On their opposing longitudinal edges these strips are provided with stringers 12, 13 upon which are respectively mounted two longitudinal rows of coupling members 14, 15 the members of the row 14 being provided on the rear edges with sockets 16 and the opposite ends of the members 15 being provided with claws 17 which engage with the sockets of the companion coupling members. Upon successively moving the opposing sockets and claws of the two rows of coupling members toward each other at an angle the same are progressively interlocked and in like manner the same may be unlocked in the reverse order by moving the opposing sockets and claws angularly away from each other.

Adjacent to the lower ends of the two rows of coupling members the strips are detachably connected by an eye 18 secured to one strip, and a hook 19 arranged on the other strip and engaging with said eye.

The coupling members are connected and disconnected by the following means, which is constructed in accordance with my invention:

The numerals 20, 21 represent the two

sections of a longitudinal movable slide, each of which is constructed in the form of a channel, the outer open or slotted side 22 of which embraces one of the rows of coupling members so as to be capable of sliding lengthwise thereon, and the inner closed sides 23 of both sections being adapted to abut against each other as shown in Fig. 2. These two slide sections are detachably connected by a lock having a wide body 24 slideable lengthwise in the slide section 20 and provided with a narrow beak 25 slideable lengthwise into and out of the front end of the other slide section 21. When the body and beak of the lock are thus engaged with the two slide sections, the latter are held with their closed inner sides in engagement and the same are held against longitudinal relative movement but compelled to move together by an alining pin 26 arranged on the inner wall of the slide section 21 and engaging with an opening or recess 27 in the inner wall of the other slide section, as shown in Figs. 2 and 3.

For the purpose of retaining the lock in its operative position a catch lever 28 is provided which is pivoted on a post 29 having a reduced lower portion 8 secured in an opening 9 in the lock body and projecting through a longitudinal slot 30 in the top of the slide section 20, the front end of this catch lever being bent inwardly to form a catch 31 which normally projects through the upper end of the slot 30 and into engagement with a recess 32 in the body of the lock and a shifting lever pivoted on the rear arm of said catch lever and provided at its inner end with a cam 34 adapted to engage the outer side of the slide section 20 and at its outer end with a finger piece 35, whereby the same is manipulated.

When the sections of the slide are thus locked together the same form a unit which operates in the usual manner of the slides heretofore known for successively engaging and disengaging the rows of coupling members on the opposing longitudinal edges of the parts on which they are mounted, whereby the joint between the connected parts is closed when the slide is run up and the joint is opened when the slide is run down.

When however it is desired to completely disconnect the two parts which carry the coupling members the hook and eye at the lower ends of the coupling members are disconnected and the shifting lever is turned so that the low part of the face on its cam stands opposite the slide section 20 at which time the catch lever is disengaged from the body of the lock. The latter is now released and free to be moved upwardly by means of the finger piece 35 for disengaging the beak of the lock from the slide section 21, thereby unlocking the slide sections from each other and permitting them to be sepa-

rated. When this is done the parts of the garment or similar article provided with this fastening may be completely separated along the meeting edges which are normally joined, thus permitting of opening a wide space 70 between these edges so as to render the several parts more accessible and also more convenient in use. This is particularly desirable in the case of coats, jackets or the like which can be put on and taken off like an ordinary coat much more easily than if the same have to be drawn over the head for this purpose. Such division of the slide is also useful for opening and closing the covers of receptacles inasmuch as the provision of means for detachably connecting the sections of a divided slide permit of more extensive and convenient access to the interior of the receptacle.

I claim as my invention:—

1. A fastener comprising two rows of coupling members adapted to be interlocked and to be mounted on the parts to be connected, a slide having two channel sections adapted to receive said rows of coupling members, means for detachably connecting said sections, comprising a lock having a body movable lengthwise in one of said sections and a beak adapted to engage the other section, and means for alining said sections relative to each other.

2. A fastener comprising two rows of coupling members adapted to be interlocked and to be mounted on the parts to be connected, a slide having two channel sections adapted to receive said rows of coupling members, means for detachably connecting said sections comprising a lock having a body movable lengthwise in one of said sections and a beak adapted to engage the other section, a pin arranged on one of said sections, and the other section having a recess 95 relative to receive said pin.

3. A fastener comprising two rows of coupling members adapted to be interlocked and to be mounted on the parts to be connected, a slide having two channel sections adapted to receive said rows of coupling members, means for detachably connecting said sections comprising a lock having a body movable lengthwise in one of said sections and a beak adapted to engage the other section, and means for retaining 115 said lock in its operative position.

4. A fastener comprising two rows of coupling members adapted to be interlocked and to be mounted on the parts to be connected, a slide having two channel sections adapted to receive said rows of coupling members, means for detachably connecting said sections comprising a lock having a body movable lengthwise in one of said sections and a beak adapted to engage the other section, means for retaining said lock 120 in its operative position, comprising a post 125

arranged on the body of said lock and slid- adjacent section and a finger piece for ma-
able in a slot in one of said sections, a catch nipulating the shifting lever and associated
lever pivoted on said post and adapted to parts. 10
pass at one end through said slot and into a In testimony whereof I hereby affix my
recess in said body, and a shifting lever signature.
pivoted on the other end of said catch lever
and having a cam adapted to engage the
